UNITED STATES PATENT OFFICE

137,421

DESIGN FOR GRAVE MARKER

Jay Rasmussen, Madison, S. Dak.

Application December 2, 1943, Serial No. 111,880

Term of patent 14 years

To all whom it may concern:

Be it known that I, Jay Rasmussen, a citizen of the United States, residing at Madison, in the county of Lake and State of South Dakota, have invented a new, original, and ornamental Design for a Grave Marker, of which the following is a specification, reference being had to the accompanying drawing, forming part thereof.

Figure 1 is a front elevational view of a grave marker showing my new design,

Figure 2 is a side elevational view, and
Figure 3 is a top plan view thereof.

I claim:

The ornamental design for a grave marker,
as shown.

JAY RASMUSSEN.
